TREATMENT OF MOTOR FUEL

Vasili Komarewsky, Chicago, Ill., assignor to
Universal Oil Products Company, Chicago, Ill.,
a corporation of Delaware

No Drawing. Application April 30, 1934,
Serial No. 723,179

2 Claims.

(Cl. 44—9)

This invention relates more particularly to the treatment of motor fuels of inferior knock rating such as gasolines produced in the primary non-destructive distillation of paraffinic and some 5 mixed base crudes, although it may also be applied to analogous low boiling cracked products.

More specifically the invention is concerned with a process whereby the hydrocarbons responsible for the knocking tendencies of the fuel are 10 converted into compounds of a more cyclic character by condensation reactions with aromatic hydrocarbons, and in this sense the process may be looked upon as one of "arylation."

Owing to the demands made by present day 15 high compression automobile engines, petroleum refiners are confronted with the problem of increasing the anti-knock value of their straight run gasoline fractions which are seldom suitable for use unless they are blended with high anti-knock fuels such as, for example, gasoline produced by intensive cracking operations upon heavy fractions of petroleum or low boiling aromatic fractions from coal and other tars. As an alternative 20 to blending operations, cracking or "reforming" 25 may be resorted to, but this is frequently an expensive procedure involving the use of equipment built to withstand temperatures of 950° F., or over and pressures in the neighborhood of 500 pounds per square inch. In addition, the losses are excessive, frequently running as high as 25% when 30 a paraffinic gasoline is brought up to an octane number of approximately 65 to 70.

A further alternative for increasing the knock rating of straight run gasolines consists in the use 35 of small quantities of chemical compounds currently known as "dopes". These compounds are generally costly and the operation of blending them in the proper quantities with gasoline involves special equipment so that this method of 40 procedure has its own particular disadvantages.

The hydrocarbons responsible for the poor knocking tendencies of gasolines are evidently the straight chain paraffins as shown by researches with pure compounds of this character. The iso-paraffins having a more compact structure have 45 a much higher knock rating than the normal compounds. In the case of olefins the compounds having higher knock ratings are those in which the double bond is nearest the center of the molecule. The rule regarding the compactness of structure applies to unsaturated chain compounds 50 as well as paraffins.

In the case of simple cyclic hydrocarbons the aromatics have better knock rating than the 55 naphthenes, and both groups increase in anti-knock value up to some maximum as the ring hydrogens are substituted by aliphatic radicals. Thus toluol and ethyl benzol have considerably higher knock ratings than benzol itself.

60 The foregoing brief resume of the established

relationships between hydrocarbon structure and anti-knock value is given to indicate the reasons for the increase of anti-knock value observed in gasolines when treated by the present process, although the entire range of the reactions involved in different cases is not known and cannot be followed owing to the complex character of the starting materials and the products formed. 5

In one specific embodiment the present invention comprises the treatment of gasolines of inferior knock rating, particularly straight run gasoline, with cyclic hydrocarbons in the presence of aluminum chloride and hydrogen chloride. 10

It is a feature of the present process that reactions are brought about at temperatures and pressures where aluminum chloride has substantially no effect upon straight run gasolines in the absence of aromatic hydrocarbons. As will be disclosed in later examples, temperatures of from 100 to 150° C., are suitable and it is hardly ever 20 necessary to exceed the last named temperature. The pressures developed in the course of the reactions will depend upon numerous factors such as the temperature, the character of the particular gasoline undergoing treatment, the ratio of 25 gasoline to aromatic, the percentage of aluminum chloride used and the intimacy of contact obtained, etc. In any event the pressures are not excessive and will seldom exceed 400 pounds per square inch. It is preferable to use relatively 30 long times of contact rather than increased temperatures since the former tend to further the desired reactions of condensation between the gasoline and aromatics and lessen the tendency to decomposition with attendant high gas losses 35 and the depreciation of the aluminum chloride due to the formation of hydrocarbon addition complexes of varying stability.

In carrying out the operations of the process best results are obtained when employing the so-called batch operation. Thus suitably proportioned mixtures of gasoline and aromatics such as benzol, toluol, xylols and even semi-refined low boiling coal and other tar distillates are heated 45 in pressure vessels in the presence of dry anhydrous aluminum chloride and hydrochloric acid gas for periods of from approximately 5 to 20 hours. In order to insure effective contact between the solid catalyst and the liquids undergoing reaction, vigorous mechanical agitation by 50 means of paddles or other devices may be employed or the contents of the pressure vessel may be circulated by outside pumps through tubular elements and back to the main supply of liquid, the heat necessary for maintaining the required 55 temperature being supplied to the tubular element, in accordance with well-known procedure in oil cracking and distilling operations. As the reactions progress a certain amount of fixed gases will be produced and these may be released auto- 60

5 matically at some predetermined pressure in order to maintain operating conditions constant. Under normal conditions there will be substantially no vaporization of gasoline boiling range constituents, though if this occurs the evolved vapors and gases may be passed through condensers and the low boiling gasoline fractions recovered and reserved for future blending.

10 Following the completion of the reactions the hydrocarbon liquid layer above the spent catalyst may be pumped to units designed to distill, fractionate and recover gasoline boiling range constituents. Fractions boiling higher than the end point desired in the finished gasoline may be 15 added to a subsequent treatment if found suitable.

15 It is a further feature comprised within the scope of the present invention to react selected fractions of low knock rating gasoline with selected aromatic fractions to obtain maximum efficiency in the development of high anti-knock characteristics. The selection of individual fractions and the use of different aromatics or aromatic mixtures to combine therewith will be 20 determined largely by experiments since it is not possible to predict the combinations which will give the most beneficial results.

25 The following data embodies the results of runs made with particular fractions of straight run gasolines from Pennsylvania and Mid-Continent fields. Two parts by weight of gasoline and one part by weight of benzol were heated in the presence of 10% by weight of dry aluminum chloride and 0.5% by weight of hydrogen chloride at 30 a temperature of 100° C. for 20 hours. The maximum pressure developed was approximately 500 35 pounds.

place with the lighter gasoline fractions. The octane numbers were run by the so-called motor method, which is a more severe test than the older "research method" and is usually more severe in rating materials of higher octane number. 5

10 During the treatments which gave the results shown above, pressure was maintained at about 500 pounds per square inch and approximately 10% by weight of gas was evolved which contained about 70% of isobutane. The remaining 5% loss was due to the formation of high boiling 15 addition compounds between aluminum chloride and heavy hydrocarbons probably of a polymerized character. 15

20 The preceding specification and the data showing the results obtained by the use of the present invention show its character and value over present practice but they are for illustrative purposes 20 only and are not to be construed as imposing undue limitations upon its broad scope.

25 I claim as my invention:

23 1. A process for improving a straight run petroleum fraction boiling within the gasoline range, which comprises adding to said fraction an aromatic hydrocarbon boiling within the gasoline range and reacting the aromatic with a portion of the petroleum fraction to arylate low anti-knock constituents of the latter and form therein 30 condensation products of increased anti-knock value boiling within the gasoline range. 30

23 2. A process for improving a straight run petroleum fraction boiling within the gasoline range, which comprises adding to said fraction an aromatic hydrocarbon boiling within the gasoline range and reacting the aromatic, in the pres- 35

40	Kind of gasoline	Boiling point of gasoline ° C.	Boiling point of gasoline-benzene mixture before the reaction ° C.	Boiling point of mixture after the reaction ° C.	Oct. No. of the mixture before reaction	Oct. No. of the mixture after reaction	40
45	Pennsylvania str. run.....	75-100	75-100	35-195	65	75	
	Pennsylvania str. run.....	100-125	80-125	35-200	59	67	
	Pennsylvania str. run.....	125-150	80-150	35-200	51	57	
50	Mid-Continent str. run.....	75-100	75-100	36-200	67	75	
	Mid-Continent str. run.....	100-125	80-125	32-210	61	69	50
	Mid-Continent str. run.....	125-150	80-150	35-195	59	67	

55 It is to be observed that the boiling range of the primary gasoline-aromatic mixtures was extended in all cases as a result of the treatment although not outside of the gasoline boiling range. It may be further noted that, while there is an increase in octane number in all cases as a result of the treatment, the greatest increase takes

55 ence of aluminum chloride and hydrogen chloride, with a portion of the petroleum fraction to arylate low anti-knock constituents of the latter and form therein condensation products of increased anti-knock value boiling within the gasoline range.

VASILI KOMAREWSKY.
